UNITED STATES PATENT OFFICE.

ELIJAH C. SHERMAN, OF MONTROSE, PENNSYLVANIA.

DESIGN FOR A GAME-BOARD.

SPECIFICATION forming part of Design No. 20,478, dated January 13, 1891.

Application filed October 18, 1890. Serial No. 368,608. Term of patent 7 years.

To all whom it may concern:

Be it known that I, ELIJAH C. SHERMAN, a citizen of the United States, residing at Montrose, in the county of Susquehanna and State of Pennsylvania, have invented certain new and useful Improvements in Designs for Game-Boards; and I do hereby declare the following to be a full, clear, and exact description of the invention, such as will enable others skilled in the art to which it appertains to make and use the same.

My design especially relates to that class of game-boards for use in playing quoits.

In the drawing the design is represented as stamped or printed upon a square piece of cloth.

The design is printed or stamped with a black background containing a number of white concentric rings *a*, the central one of which is a little larger than a quoit, and concentrically within it is a white circle *b*. One of the outer rings *a* is broken at equal intervals, preferably at four different places, at which places are small white rings *d* of the same

size as the central ring *a*. Like the central 25 ring *a* the rings *d* contain concentric white circles. In the spaces between each of the concentric rings are white circles *c*, similar to circle *b*, and they form with the latter a radial row of white circles. The white circles 30 preferably each contain a numeral, as shown.

What I claim is—

The herein-described design for game-boards, the same consisting of a series of concentric rings, small rings arranged in concentric series at regular intervals and intersected by one of the concentric rings, said small rings and the inner concentric ring containing small circles, and a radial series of small circles arranged one between each pair of concentric 35 rings, as shown and described.

In testimony whereof I affix my signature in presence of two witnesses.

ELIJAH C. SHERMAN.
